UNITED STATES PATENT OFFICE

EARL B. WHITEHEAD, OF NORWICH, CONNECTICUT, ASSIGNOR TO ATLANTIC CARTON CORPORATION, OF NORWICH, CONNECTICUT, A CORPORATION OF CONNECTICUT

CARTON

Application filed December 3, 1930. Serial No. 498,660.

This invention relates to improvements in cartons and is directed more particularly to foldable cartons.

The principal objects of the invention are the provisions of a carton blank which is so shaped and arranged that a carton may be formed therefrom which is adapted for use as a shipping container as well as a display container.

10 According to the novel features of the invention a carton blank is made from a single piece of material which is so shaped and arranged that the carton when set up will have overlapping parts locked in their overlapping relation, whereby the carton is suitably adapted for shipping purposes as well as for displaying the contents thereof.

15 Various novel features and advantages of the carton of the invention will be more fully pointed out hereinafter. In the form at present preferred the invention will be described in connection with the accompanying drawing wherein:

Fig. 1 is a plan view of the carton blank 25 of the invention shown in a flat condition.

Fig. 2 is a perspective view of the blank in a partly set-up position.

20 Figs. 3 and 4 are partial plan and longitudinal sectional views respectively taken at the forward end of the carton when set up showing how the forward end flaps are locked in place.

Fig. 5 is a perspective view showing the carton set up for shipping purposes, and

25 Fig. 6 is a perspective view showing the carton arranged for display purposes.

Referring now to the drawing in detail the invention will be more fully described.

The carton blank of the invention as in Fig. 1 comprises relatively foldable elements as follows: A lower wall portion 4 has side walls 6 hinged at the sides thereof. To the opposite ends of these side walls front end tabs 8 and rear end tabs 10 are hinged.

40 The side walls 6 preferably comprise outer and inner plies of material 11 and 12, which may be secured together by adhesive material so that the side walls are relatively stiff and firm. The side wall sections are 45 bendable on score lines 13 and the tabs 8 and

10 are bendable on score lines 15 and 17 respectively.

The front end tabs 8 are arranged to be folded into overlapping relation when the side walls are bent upwardly into parallelism. The rear end tabs 10 are provided with interlocking ears 14 as shown, so that when the side walls 6 are arranged in parallelism these rear end tabs may be folded inwardly and into overlapping and interlocking relation.

A primary easel flap 20 is provided at the upper or rear end of the bottom wall 4 and is bendable on a score line 21. A secondary easel flap 22 is located at the outer side of the flap 20 and is likewise bendable on a score line 23. Easel tabs 24 at either side of the flap 22 are bendable on score lines 25 and have ear pieces 26 which are receivable in slots 28 adjacent the score lines 13. A rear end wall section 30 is bendable on a score line 31 and from this extends a cover 32 consisting of a supporting panel 34 and a display panel 36. The panels 34 and 36 are relatively bendable on a score line 37 and the panel 34 is bendable on a score line 35. A semi-circular cut-out 39 is provided in the cover adjacent the score line 37 so that the display panel 36, when the panels 34 and 36 are bent relative to one another, 50 may have an upwardly extending portion 40. A front end tuck 42 is bendable on a score line 43 at the outer end of the display panel 36.

At the lower or forward end of the bottom wall 4 there are provided locking wall sections 44 and 46, the former of which is bendable on the score line 45, while they are relatively bendable on a line 47. The section 44 may be called an outer locking wall 55 section and the section 46 may be called an inner locking wall section. To the end of the section 46 there is provided a locking tab 50 bendable at 49. This preferably has diverging side edges 52 so that the end of the tab at least is slightly wider than the bottom wall 4 as will hereinafter be described.

The carton blank described may be made from any suitable material and shaped of 60

course to provide cartons of various dimensions and proportions. When so made of cardboard or similar material it will be properly scored at the places indicated so that the various elements thereof may be folded or bent relative to one another.

In setting up the carton the easel flap 20 is bent downwardly from the bottom wall and then the section 22 is bent upwardly 10 to overlie the said section 20 with the rear end wall section 30 extending upwardly from the bottom wall and with the cover 32 extending beyond. In this position the side walls are bent upwardly and the rear end 15 tabs 10 are locked together behind the section 30 whereby the side walls will be held in an upright position as shown in Fig. 2.

The front end tabs 8 are next turned inwardly to overlap one another. Then the 20 section 44 is bent upwardly to overlie the outer side of the tabs 8 and the section 46 is bent inwardly and over to overlie the rear side of said tabs 8. In this way the overlapping tabs 8 are held or locked between the 25 elements 44 and 46 and the locking tab 50 is forced downwardly between the side walls as shown in Figs. 3 and 4.

Inasmuch as the locking tab 50 is slightly wider than the bottom of the box, and 30 consequently slightly wider than the distance between the said walls, the side edges of the tab are frictionally engaged by and between the side walls and is held against displacement whereby the elements 44 and 35 46 are held in place to lock the overlapping tabs 8. That is, the tab 50 is wedged between the walls and is held thereby against displacement.

In this way the blank is set up for a receptacle adapted to receive articles and when 40 filled the cover 32 is folded downwardly and forwardly on the score line 35 so that the front end tuck 42 may be inserted adjacent the front wall at the front end of the carton 45 and the forward face of an adjacent article. As this tuck 42 is inserted between an object in the carton and the front wall, the cover will of course be held in place. The easel flap 20 is bent on the scoring line 21 50 so that it overlies the lower wall of the carton and the easel flaps 24 are brought upwardly at the sides of the carton, as shown in Fig. 5. It will be observed that in this condition the carton is suitable for shipping purposes and that it has no projecting parts whereby the cartons are adapted to be packed or stacked most advantageously.

When it is desired to arrange the carton 60 for display purposes, the cover is bent upwardly on the score line 35 and doubled upon itself on the score line 37 so that the tab 42 may be inserted between the rear end wall section 30 and the adjacent side of the rear-most article in the carton. Then the easel 65 flap 20 is bent downwardly so that the easel

flaps 24 may be bent forwardly on the score line 25 to facilitate the insertion of the elements 26 into the slots 28. In this way the easel flaps 24 are held in position whereby the flaps 20, 22 and 24 serve as a support 70 at the rear end of the carton for tilting it, after the manner shown in Fig. 6. The inner plies 12 are notched at their free edges as clearly shown in Figures 1 and 2, to accommodate the ear pieces 26 when the latter 75 are disposed through the respective slots 28. This arrangement will permit the ears 26 to lie in the same plane as the inner plies 12 of the sides of the carton, when the carton is assembled and set up in a display position. By having the ears disposed within the notches, the same will not interfere with the insertion or removal of the packages from 80 the carton.

It may be desirable in some cases to provide the easel flaps 24 with interlocking parts rather than to insert a part of the flaps in slots 28. An interlocking arrangement of these flaps will hold them in position so that 85 they may serve as a proper support for tilt- 90 ing the carton.

It will be noted that the carton is made from a single piece of material which is formed with relatively bendable or foldable elements whereby a carton may be readily 95 and easily set up for serving as a shipping container or for display purposes. It will be noted that the overlapping flaps at the forward end of the carton are held in their overlapping position by the locking sections which embrace opposite sides thereof and that the locking sections are held in place by a relatively wider section which frictionally 100 engages or is wedged between the inner sides of the side walls.

As a special feature it will also be noted that interlocking end tabs at the rear of the carton are concealed on the inner side of the carton by the wall section 30 so as to not only 105 be protected but do not impair the appearance of the display effect.

Having described the invention in the form at present preferred, what I now desire to claim and secure by Letters Patent of the United States is:

1. A carton comprising in combination, a bottom, sides and ends, said sides comprising inner and outer plies, said bottom having slots located adjacent the respective sides, the inner plies having notches formed in the free edges thereof in alignment with the respective slots, an easel forming flap extending downwardly from the rear end of the bottom, bendable easel forming tabs extending from the sides of said flap, ears formed on the tabs for disposition through the respective slots whereby the carton is supported in a display position, said ears being receivable in the respective notches in the 115 120 125 130

inner plies of the side walls for disposition in the same plane with the inner plies.

2. A foldable carton comprising in combination, a bottom provided with tab receiving slots adjacent its side edges, foldable side walls at the sides thereof, tabs at the forward ends of the side walls and arranged for overlapping relation, interlocking tabs at the rear ends of the side walls, a primary easel flap bendably connected to the rear end of the bottom, a foldable secondary easel flap attached to the rear end of the primary easel flap and adapted to fold thereagainst, bendable easel tabs extending from the side edges of the secondary easel flap and having portions thereof receivable in the respective slots, whereby the carton is supported by the easel flaps and the easel tabs in a set up display position, a rear wall section extending from the outer end of the secondary easel flap and adapted to be disposed against the aforementioned interlocked tabs when the carton is set up in display position, and a combined cover and display panel connected to the outer end of the rear wall section.

In testimony whereof I affix my signature.
EARL B. WHITEHEAD.
